TRAFFIC SIGNAL

Frank H. Richterkessing, Louisville, Ky., assignor to Nachod & United States Signal Co., Incorporated, Louisville, Ky., a corporation of Kentucky

Application August 24, 1928, Serial No. 301,799
Renewed June 18, 1934

10 Claims. (Cl. 177—337)

My invention relates to the control of electrically operated traffic signals primarily intended for use at the intersections of two thoroughfares.

5 The main object of my invention is to provide a means wherein an electric car approaching the intersection will take control of the traffic signal to favor the preferential movement of the car. In other words, the traffic signal will be 10 displaying "stop" and "proceed" indications periodically until a car enters a selected proximity to the intersection, wherein the periodic control of the traffic signal indications will be interrupted to cause a prolonged display of a proceed indication, on the electric line and a red stop indication for intersection traffic, for the direct purpose of expediting the movement of the car and eliminating the congestion of traffic in the front of the car. The system is so arranged that the periodic control will be restored 15 a soon as the car passes the intersection.

It will be apparent that by means of a series of such installations throughout the route of travel of an electric car, the car would be enabled to attain an express schedule with a maximum of protection which is a very essential factor when cars increase their average speed.

Briefly, it is the object of my invention to produce a traffic signal system primarily intended 20 to have a periodic display of its indications, but equipped with means, automatically controlled by the movement of a vehicle to prolong or control the display of a desired indication.

Another object of my invention is to produce 25 a system that works irrespective of the vehicle using "power" or not, the system as hereinafter described.

My invention resides in a new and novel combination, the construction and relation of various electrically operated switches, circuits and other parts hereinafter more fully described and disclosed in the drawing.

In the drawing accompanying my specification:

45 The single figure is a schematic drawing disclosing the general principles employed in my system.

My invention is intended primarily to be controlled by cars that are operated by means of an 50 overhead trolley wheel or current collector W_1 mounted on a car by means of a trolley pole, although it may be controlled by vehicles which are operated by other methods.

In the system shown in Fig. 1, the letter D 55 represents a trolley wire or conductor. Posi-

tioned adjacent the trolley wire or conductor D are trolley contactors $3A$ and $5A$ which are normally insulated therefrom, but are electrically connected thereto, when the current collector W_1 engages the trolley contactors $3A$ and $5A$ 5 respectively. The trolley contactor $3A$ is mounted on the trolley wire D and is placed within a selected proximity on the approach side of the intersection represented in the drawing by N , E , S , W . Contactor $5A$ is mounted on the trolley wire D , on the far side of the intersection. At the intersection the letters TS represent a traffic signal for periodically displaying "stop," "caution" and "proceed" indications for the W , E 10 electric line traffic and the intersecting, N , S 15 traffic.

I also employ an electrically operated relay R provided with two operating coils A and C , and each are energized to effect an operation of the contact plunger P when a car passes under the trolley contactors $3A$ and $5A$. The plunger P of relay R is equipped with a contact ring A_1 that normally engages contacts 34 and 35 , and is brought into this position by the energization of the coil C . When the coil A is energized the 20 contact plunger P is shifted, and the contact ring A_1 is brought into contact engagement with contacts 14 and 21 and out of contact engagement with contacts 34 and 35 . 25

I also employ in this system a motor driven 30 time element device for controlling the circuits for the periodical display of the "stop," "caution" and "proceed" signals. The letter M represents a single phase alternating current induction motor and is equipped with a constant potential 35 field coil H and controlling field coils represented by J and K . The motor M is equipped with a copper or aluminum disc 74 , and the principle of the operation of such a motor is well known to those skilled in the art. The magnetic field produced by the constant potential and controlling field coils combine to form a rotating field; that is, the relation of these two fields for a complete cycle by one-quarter periods of the same, is approximately a 90 degree lag of one over 40 the other. This continuous motion of the field induces eddy currents in the copper or aluminum disc 74 , which react to produce rotation in the same manner as in the rotor of an induction motor. Since the rotation produced by the rotary field is a combination of the constant potential and controlling fields, it can be readily seen that the removal or reversal of one of the fields, namely the controlling field, would stop the disc 45 or cause the disc to run in a reversed direction. 50

55

In the system herein described and disclosed, I take advantage of this novel feature which plays an important part in the advancement of this art. It is well known to those skilled in the art that while the motor M is in a running condition, if the coil terminals of the controlling field coils J and K were short circuited, the collapsing of the controlling field and the rising of the constant potential field would react in a manner to retard and practically instantly stop the rotation of the disc, and as the coils of the controlling field J and K are short circuited, they would act as a shading coil and their field and the constant potential field would react in such a manner as to produce a reversal in the former direction of the disc. The disc 74 drives the controller segments 51, 52, 53 and 54, through the shaft 55. With reference to the drawing, it can be clearly seen how the rotation of the cam segments in the direction of the arrow 56 produce a subsequent opening and closing of the various contacts controlling the circuits of the signal indications, and do not believe that a further explanation of how this is accomplished is necessary at this point, but will be taken care of more completely in a further detailed description.

The dotted outline figure TS is a symbolic representation of a traffic signal, housing three decks 30 of signal indications to display in four directions. In the upper deck, the red lenses 62 and 63 that face N and S on the intersection, and the green lenses 64 and 65 that face W and E, on electric line, have a common light source represented by L4. In the center deck the four lenses 66, 67, 68, and 69 display an amber or "caution" indication and each is provided with an independent light source, lens 66 having a light source represented by Lt, lens 67 having a light source represented by L1, lens 68 having a light source represented by L2, lens 69 having a light source represented by L2 and lens 69 having a light source represented by L. These indications, however, are not displayed simultaneously, but are displayed at intervals that will be more clearly described in a later description. In the lower deck the green lenses 70 and 71 that face N and S on the intersection and the red lenses 72 and 73 that face W and E on the electric line, have a common light source represented by L5. For clarity of the description each of the three decks are shown in a plan view, and this must be taken into consideration when the signal system is described so that the signal indications will be given for their proper directions.

The indications of the traffic signal are normally displaying periodically; that is, each signal indication displays a certain predetermined time before the display of another signal indication occurs, all of which occurs in a definite sequence of a predetermined cycle. Starting for instance at an arbitrarily selected time of the cycle, we have a display of a green signal in both directions for the W and E electric line traffic, and a display of a red signal in both directions for the N and S intersecting traffic, the circuit for these indications being completed from the positive side of the line BX, thru wire 3, wire 5, wire 6, contact arm 23 of the motor driven time element, contact 24 of contact arm 23, contact 25 of the stationary contact arm 26, thru the stationary contact arm 26, wire 27, to the signal lamp L4, which is a common light source for the four indications, wire 17, wire 16, wire 15, to the common return of the line CX. With reference to the drawing 75 it will be seen that these indications will con-

tinue to display until the cam segment 51 permits the contact arm 23 to disengage the contacts 24 and 25, which is, for one half of the total cycle. It will also be noted, that just as the cam segment 51 nears the end of its period, the cam 52 embraces the contact arm 28 of the motor driven time element, and causes contacts 29 and 30 to be brought into contact engagement, resulting in a display of a "caution" signal or a short interval indication to warn the moving electric line traffic that a change is about to be made in the signal indications. It will be well to note that this indication is not given to all four sets of the traffic, but to the traffic that is in motion only, and is given with the green "proceed" electric line signal indicating. The circuit for "caution" signal for the moving W, E electric line traffic being completed from the positive side of the line BX, thru wire 3, wire 5, wire 7, wire 8, contact arm 28 of the motor driven time element, contact 29 of contact arm 28, contact 30 of the stationary contact arm 31, thru the stationary contact arm 31, wire 32, wire 33, contact 34 of relay R, thru the contact ring A1 on the plunger P of relay R, contact 35 of relay R, wire 36, wire 37, to the lamp L which is the light source for lens 69 facing the W electric line traffic. It will be noted that wire 36 connects two branch circuits, one connection to wire 37 as described and the other to wire 38 which feeds the light source for the lens facing the E electric line traffic. The circuit for this being completed from the wire 37 to the branch wire 38, thru wire 38 to lamp L2, which is a light source for lens 68 facing the E electric line traffic. Both lamps L and L2 have a common connection to the common return thru wire 19 feeding to wire 18, thru wire 18, wire 16, wire 15, to the common return of the line CX. Cams 51 and 52 disengage their respective contact arms simultaneously, and instant to this operation cam 54 embraces the contact arm 46 of the motor driven time element and causes contacts 47 and 48 to be brought into contact engagement. These operations resulted in the former described indications going to darkness and the display of a red indication for the W, E electric line traffic and a green indication for the N, S intersecting traffic. It will be noted that the display of these indications caused the moving traffic to come to a stop and the traffic that was at stop to be permitted to proceed. The circuit for the latter indications being completed from the positive side of the line BX thru wire 3, wire 5, wire 7, wire 9, wire 11, contact arm 46 of the motor driven time element, contact 47 of contact arm 46, contact 48 of the stationary contact arm 49, wire 50, to the signal lamp L5 which is a common light source for the four indications, wire 20, wire 18, wire 16, to the common return of the line CX.

With reference to the drawing, it will be seen that these indications will continue to display until the cam segment 54 permits the contact arm 46 to disengage the contacts 47 and 48, which is, as shown one half of the total cycle. It will also be noted that just as the cam segment 51 nears the end of its period, the cam 53 embraces the contact arm 39 of the motor driven time element causing the contacts 40 and 41 to be brought into contact engagement, and resulting in a display of a "caution" signal or a short interval indication to warn the moving intersecting traffic that a change is about to be made in the signal indications. It will be well to note that this indication is not given to all four sets of traffic, but to

the traffic that is in motion only, and is given with the green "proceed" signal indicating. The circuit for the "caution" indication for the moving N, S intersecting traffic being completed from the positive side of the line BX thru wire 13, wire 5, wire 7, wire 9, wire 10, contact arm 39 of the motor driven element, contact 40 of contact arm 39, contact 41 of the stationary contact arm 42, thru the stationary contact arm 42, wire 43, wire 10 44, to lamp L1, which is the light source for lens 66 facing the N intersecting traffic. It will be noted that wire 43 connects two branch circuits, one connection to wire 44 as described and the other to wire 45 which feeds the light source for 15 the lens facing the S intersecting traffic. The circuit for this being completed from wire 43 to the branch wire 45, thru wire 45 to lamp L3 which is the light source for lens 67 facing the S intersecting traffic. Both lamps L1 and L3 having a 20 common connection to the common return thru wire 19 feeding to wire 18, thru wire 18, wire 16, wire 15, to the common return of the line CX. Cams 53 and 54 disengage their respective contact arms simultaneously and instant to this operation cam 51 embraces the contact arm 23 of the motor driven time element, and the signal indications are continuously displayed in same 25 cycle as just described.

When the current collector W1 engages the 30 trolley contactor 3A, the contactor will be electrically connected and of the same potential as the trolley wire, and the coil A of relay R will be energized and shift the plunger P of relay R, bringing the contact ring A1 into contact 35 engagement with contacts 14 and 21, and out of contact engagement with contacts 34 and 35. The circuit for the energization of coil A being completed from the trolley wire D, thru the current collector W1, thru the contact strip of the 40 trolley contactor 3E, wire 58, coil A of relay R, wire 59 to ground G. As soon as the current collector disengages the trolley contactor, the coil A of relay R will become deenergized but the plunger P will remain in the shifted position. 45 At this point it will be well to note the circuit of the motor M of the motor driven time element device. The constant potential field coil H of the motor M is connected directly across the line. This circuit being completed from the 50 positive side of the line BX thru wire 1, field coil H of motor M, wire 2, to the common return of the line CX. The controlling field coils J and K of the motor M are connected in series, and in series with the resistor R1, and connected 55 across the line. This circuit being completed from the positive side of the line BX thru wire 3, wire 4, field coil J, field coil K, wire 12, resistor unit R1, wire 15, to the common return of the line CX. The shifting of the plunger P of 60 relay R resulted in the opening of contacts 34 and 35 of relay R, that normally completed the "caution" signal circuit for the W, E electric line traffic, and closed contacts 14 and 21 thru the contact ring A1. This operation did not affect 65 the signal display, however, unless the signal was displaying the electric line "caution" indication, or not until the timer passed thru the necessary cycle to establish this circuit. After the automatic motor driven time element device passed 70 thru the necessary cycle and encountered the display of a green "proceed" indication for the W, E electric line traffic and a display of a red "stop" indication for the N, S, intersecting traffic, the signal indications continued to display 75 under the influence of the automatic motor

driven time element until the time for the display of the "caution" indication for the W, E electric line traffic.

As soon as the contacts closed, however, the "caution" signals were not displayed, as the circuit was opened thru the opening of contacts 34 and 35 of relay R, as heretofore described. But the closure of this circuit, at the automatic motor driven time element, resulted in a short circuit of the controlling field coils J and K of the motor M, thru the resistance unit R1, and the motor was stopped; that is, it continued to oscillate at this point, running forwards and backwards, opening and closing the contacts, on the motor driven time element, controlling this 10 circuit. This circuit was under the control of cam 52 on the automatic motor driven time element, and was completed from the positive side of the line BX, thru wire 3, wire 5, wire 7, wire 8, contact arm 28 of the automatic motor driven 20 time element, contact 29 of contact arm 28, contact 30 of the stationary contact arm 31, thru the stationary contact arm 31, wire 32, wire 22, contact 21 of relay R, contact ring A1 of plunger P on relay R, contact 14 of relay R, wire 13, 25 resistance unit R1, wire 15 to the common return of the line CX. The closure of contacts 29 and 30, resulted in placing positive thru wire 12 on the controlling field coil K, and as the other coil J, which is in series with coil K, is constant- 30 connected to the same source thru wires 4 and 3, no current flowed in the controlling field coil circuit, and as heretofore described the motor reversed its direction as shown by the arrow 35 51. The reversing of the motor rotation resulted in an opening of the contacts controlling the shunt circuit, and permitted the motor to run forward until the contacts were again closed. It can be seen that this condition would continue as long as the shunt circuit was established 40 in this manner, and retain the display of a green signal for the W, E electric line traffic and a red "stop" indication for the intersecting traffic, however, as soon as it would be removed the motor would continue to run its normal direction 45 as shown by the arrow 56. The purpose of having the motor reverse its direction is to always have a complete display of the "caution" indication when the motor control is restored. It can be seen that some time is involved in bringing the motor disc 74 to stop, and this time is absorbed in the W, E electric line "caution" signal display time, after the contacts controlling the circuit were closed. It can be seen that since the total time for this signal display is very short, 50 that any time subtracted from it would be very noticeable, and since this time is variable would defeat its designated purpose. Therefore, by stopping and reversing the motor, as described and employed in this system, irrespective of 55 where the motor is stopped or caused to be stopped by the application of a shunt under the control of the "caution" signal contacts, a full "caution" signal display would be rendered when the system is restored to its periodic control. 60

After the traveling current collector W1 travels its course, it passes the intersecting N, S, W, E and comes into contact engagement with the trolley contactor 5A mounted on the trolley wire D. The contact engagement of the current collector W1, and trolley contactor 5A resulted in a circuit being completed from the trolley wire D, thru the current collector W1, thru the contact strip of trolley contactor 5A, wire 60, coil C of relay R, wire 61 to ground G, and the coil C 70 75

was energized and the plunger P of relay R was shifted. The movement of the plunger P of relay R, removed the contact engagement of the contact ring A1 of relay R with contacts 14 and 21, and brought it into contact engagement with contacts 34 and 35. This operation removed the shunt circuit on the controlling field coils J and K that was completed thru the contacts 21 and 14, and established an immediate display of a 10 "caution" signal for the W, E electric line traffic, the circuit being completed from the positive side of the line BX thru wire 3, wire 5, wire 7, wire 8, contact arm 28 of the automatic motor driven time element, contact 29 of contact arm 28, contact 30 of the stationary contact arm 31, thru the stationary contact arm 31, wire 32, wire 33, contact 34 of relay R, contact ring A1 of plunger P on relay R, contact 35 of relay R, wire 36, wire 37 to lamp L which is a light source for lens 20 69 facing the W electric line traffic, and also thru wire 38, which taps to wire 36 at its terminating point with wire 37, to lamp L2 which is a source for lens 68 facing the E electric line traffic. Both lamps L and L2 have a common 25 connection to the return wire thru wire 19, to wire 18, thru wire 18, wire 16, wire 15, to the common return of the line CX. The movement of the current collector WI past the trolley contactor 5A resulted in the system being restored to a normal; that is the signal indications 30 would now be displayed periodically as heretofore described until a following car would take control of the automatic motor driven time element to prolong the green "proceed" indication 35 for its course of travel, until it passed the street intersection.

It would be well to note that in this system the periodic control of the signal indication is disturbed only when the running time of the 40 car from trolley contactor 3A to trolley contactor 5A is greater than the green period of the signal for the W, E electric line traffic, or dependent upon what time of the display, it entered the said section. In any case the car will 45 take control of the signal for an added time long enough to permit its passage over the intersection, wherein the signal will immediately display an amber "caution" indication and then display a red "stop" indication for the W, E electric line traffic and a green "proceed" indication 50 for the NS intersecting traffic under the influence of the automatic motor driven time element.

It is obvious to those skilled in the art, that 55 although the system is shown and described in the drawing and specification for operation on a single track electric line, that the system is also operable on a double track electric line.

There are, of course, modifications and arrangements of the parts and circuits which may be made from that shown in the above disclosure and which will still fall within the scope of my invention.

I claim:

60 1. A traffic signal system arranged at the intersection of a main highway and a crossroad for regulating traffic, said system comprising a plurality of signal circuits, one circuit including a signal to indicate "stop" and another to indicate "go," a normally active time controlled switch means included in the said circuit for alternately opening and closing same cyclically, vehicle operated devices in the main highway to be consecutively operated by a vehicle, and means 65 operated by said devices for rendering said time

controlled switch means temporarily inactive and retaining the said "go" signal for the main highway.

2. A traffic signaling system for regulating traffic on interfering traffic lanes; said system comprising a plurality of signal circuits, one circuit including a signal to indicate "stop" and another to indicate "go," a normally active time controlled switch means included in the said circuit for alternately opening and closing same cyclically, a vehicle operated device on one of the said traffic lanes, means operated by said device for rendering said time controlled switch means inactive and retaining the said "go" signal for the last said traffic lane, a second vehicle actuated device on the last said traffic lane, and means operated by said second device to restore the said system and time controlled switch to their normal active condition.

3. A right-of-way indicating device for interfering traffic lanes; controller means for normally periodically shifting the right-of-way indication from one traffic lane to the other; means to arrest the controller so as to maintain the right-of-way indication on one of said traffic lanes; means including a vehicle operated device on the last said traffic lane to operate the controller arresting means to maintain the right-of-way indication on the last said traffic lane, and means including a second vehicular operated device on the last said traffic lane to restore the said controller arresting means to normal and to re-establish the periodic control of the said indications by the controller.

4. In a traffic signaling device; an electrically operated right-of-way indicating device for intersecting thoroughfares; an electrically-operated motor normally operating, controller means driven by the said motor; circuit connections between the said controller and right-of-way indicating device, for normally shifting the said right-of-way indication from one thoroughfare to the other; a traffic responsive means for one of said thoroughfares having one condition of operation when traffic on the said thoroughfare is approaching the intersection and is within a certain distance thereof; and a second condition of operation for all other positions of traffic on the last said thoroughfare with respect to the intersection; and means controlled jointly by the traffic responsive means and the controller means for stopping operation of the said motor so as to retain the right-of-way indication to the last said thoroughfare when said traffic responsive means is in the first condition of operation and for restoring operation of the said motor when the traffic responsive means is in said second condition.

5. A traffic control system to be applied at the intersection of vehicle lanes and including signaling means for alternately according and interrupting right-of-way to the said lanes, normally active timer means for timing the alternating periods of right-of-way, and means responsive to the presence of a vehicle in one of said lanes approaching the intersection, for arresting the operation of the said timer to retain the right-of-way accorded to the said one lane, and means responsive to the instant the vehicle clears the intersection to restore the timer to its normally active condition.

6. A traffic control system to be applied at the intersection of vehicle lanes and including signaling means for alternately according and interrupting right-of-way to the said lanes, normally active timer means for timing the alternating periods of right-of-way, and means responsive to the presence of a vehicle in one of said lanes approaching the intersection, for arresting the operation of the said timer to retain the right-of-way accorded to the said one lane, and means responsive to the instant the vehicle clears the intersection to restore the timer to its normally active condition.

ing periods of right-of-way, and means responsive to the presence of a vehicle in one of said lanes approaching the intersection, for arresting the operation of the said timer to retain the right-of-way accorded to the said one lane, and means responsive the instant the vehicle clears the intersection to restore the timer to its normally active condition, and means for delaying the establishment of right-of-way on the other said traffic lane for a predetermined time after the said timer is restored to its normally active condition.

7. A vehicle-responsive control for "stop" and "go" signals for interfering traffic lanes comprising, in combination, a normally-energized electric motor; means operated by the said motor for actuating said signals in accordance with a predetermined cycle; a vehicle-actuated device in one of said lanes; relay means operating in response to an actuation of the said device; a normally-open relay switch closed by the operation of the said relay means; a normally-open control switch operated by the said motor, and closed during a latter portion only of the "go" signal actuation for the said one lane; and a shunt circuit for de-energizing the said motor including the said control switch and said relay switch.

8. In a traffic control system comprising "stop" and "go" signals for interfering traffic lanes; an electric motor normally operating; means operated by the said motor for actuating the said signals in accordance with a predetermined cycle; control means operated by the said motor during a latter portion only of each actuation of the "go" signal for one of said lanes; a vehicle-actuated device in the said one lane; relay means operating in response to an actuation of the said device; and means, controlled jointly by the

operation of the said control means and the operation of the said relay means, for stopping operation of the said motor so as to retain actuation of the "go" signal on the said one lane.

9. In a traffic control system comprising "stop" and "go" signals for interfering traffic lanes; an electric motor normally operating; means operated by the said motor for actuating the said signals in accordance with a predetermined cycle; a vehicle-actuated device in one of said lanes; and means, operating in response to an actuation of the said device and cooperating with the first mentioned means during a latter portion only of the actuation of the "go" signal on the said one lane, for stopping operation of the said motor so as to retain actuation of the "go" signal on the said one lane.

10. In a traffic control system comprising "stop" and "go" signals for interfering traffic lanes; timing means alternately displaying said signals to each of said lanes for predetermined times for the control of traffic; control means operated by the said timing means during a latter portion only of each display of the "go" signal for one of the said lanes; a vehicle-actuated device in the said one lane; relay means operating in response to an actuation of the said device; and means controlled jointly by the operation of the said relay means and the operation of the said control means for cooperating with the first named means to extend the time of display of the "go" signal on the said one lane beyond the time predetermined by the first named means, whereby extension in the time of display of the said "go" signal on the said one lane is held in abeyance until the said control means is operated, and provided only when the said relay means is operating at such time.

FRANK H. RICHTERKESSING.
